UNITED STATES PATENT OFFICE.

JOSEPH GLÜCK, OF NEW YORK, N.Y., ASSIGNOR OF ONE-HALF TO GEORGE VOGT, OF NEW YORK, N. Y.

ROCKING COUCH.

SPECIFICATION forming part of Letters Patent No. 712,372, dated October 28, 1902.

Application filed May 9, 1902. Serial No. 106,518. (No model.)

To all whom it may concern:

Be it known that I, JOSEPH GLÜCK, a citizen of the Empire of Germany, residing in New York, borough of Manhattan, and State of New York, have invented certain new and useful Improvements in Rocking Couches, of which the following is a specification.

This invention relates to a rocking-couch of improved construction in which the rocking of the same is easily accomplished by reason of the manner of its mounting, and when it is desired to change the couch into a stationary couch the folding legs thereof are adjusted into proper position with but slight exertion or change of position on the part of the occupant.

The invention consists of a rocking couch, comprising a couch-body pivotally mounted on a suitable base or stand, springs of elliptical form arranged between said base and couch-body, arms pivoted at the sides of the head portion of said body, and rods pivotally connecting said arms in the plane of the pivotal mounting of said couch-body with the rear portions of said base.

The invention consists, further, of certain details of construction and combinations of parts, which will be more fully described hereinafter and finally pointed out in the claims.

In the accompanying drawings, Figure 1 is a side view of my improved rocking couch, showing the same with its parts in position to permit rocking. Fig. 2 is also a side elevation thereof, but showing the same as a stationary couch. Fig. 3 is a vertical transverse section on line 3 3, Fig. 2. Fig. 4 is a vertical longitudinal section of a couch with the parts shown as in Fig. 2. Fig. 5 is a bottom plan view of Fig. 4, and Fig. 6 is an end view of the couch.

Similar letters of reference indicate corresponding parts.

Referring to the drawings, A represents a couch-body having the head portion A', said body being constructed in the usual manner, with suitable upholstering. The couch-body A is pivotally supported upon the base B by means of the pivot-brace a, arranged in the transverse plane of the center of gravity of the couch-body, which are connected with the braces b on said base. Between the base B

and the bottom of the couch-body A are arranged, at opposite sides, the springs C. Adjacent the springs the couch-body A is provided with longitudinal ways D, in which are 55 adapted to move the rectangular frames E, having their inner ends overlapping each other and connected by means of the lazy-tongs F, as shown in Figs. 4 and 5. To the outer ends of these frames E are connected 60 pivotally-mounted leg-frames G, the connection being obtained through links g.

Suitably mounted upon the bottom of the couch, as shown in Fig. 5, preferably on the brace H, is the lever H', connected at one end 65 to one of the frames E. The opposite end of the lever H' is connected with a hand-lever H², mounted on one side of the couch-body, by means of a slotted link h, which is connected with the lever H' on the under side of the 70 couch-body.

The frame of the head A' of the couch-body is provided with lugs a', as shown in Fig. 4 by dotted lines, to which are pivoted arms a². These arms are connected at their outer ends 75 with rods I, the lower ends of which are pivotally mounted on the base B, said rods being disposed in incline direction from a point approximately above the pivotal mounting of the couch to a point at its bottom considerably at one side of the pivotal mounting of the couch.

In using the couch for rocking the legs are properly in folded position, as shown in Fig. 1, and when the occupant applies pressure 85 upon the outer ends of the arms a² the couch is caused to oscillate by reason of the connection of the arms a² with the inclined rods I, pivoted on the base B. The spring C is of elliptical form and being disposed centrally 90 of the pivotal center of the couch the oscillation or rocking of the same is greatly facilitated, so that there is but little exertion on the part of the occupant.

When it is desired to change the couch into 95 a stationary one, the legs are adjusted by operating the hand-lever H², which through the intermediate braces causes the frames E to move apart simultaneously through the lazy-tongs F, so that the leg-frames G unfold 100 together to a position in which lower ends of the frames rest in contact with the floor,

whereby the rocking of the couch is totally prevented. By reversing the operation of the hand-lever the legs are caused to fold again and the couch is again adjusted for rocking.

5 Having thus described my invention, I claim as new and desire to secure by Letters Patent—

1. In a rocking couch, the combination, of a couch-body pivotally mounted on a suitable base, means connected with said base and couch-body for oscillating the latter, folding legs hinged at the ends of said body, lazy-tongs arranged on the bottom of said couch-body, links connecting said legs with the lazy-tongs for moving them simultaneously, and lever mechanism for operating the lazy-tongs, substantially as set forth.

2. In a rocking couch, the combination, of a couch-body, a base therefor, springs ar-

ranged between the same and the couch-body, 20 guideways carried by said body on the bottom thereof, sliding frames guided thereby, lazy-tongs connecting the ends of said frame, folding leg-frames arranged at the ends of said couch-body connected with said sliding 25 frames, an operating-lever mounted on the bottom of said body for actuating said sliding frames, a hand-lever on the side of said couch-body connected with said operating-lever, and means for oscillating the couch, 30 substantially as set forth.

In testimony that I claim the foregoing as my invention I have signed my name in presence of two subscribing witnesses.

JOSEPH GLÜCK.
